J. DAY

SPIRIT LEVEL

Filed March 1, 1926

Inventor

Jacob Day

Larry Haney, Attorneys

UNITED STATES PATENT OFFICE.

JACOB DAY, OF DULUTH, MINNESOTA.

SPIRIT LEVEL.

Application filed March 1, 1926. Serial No. 91,605.

This invention relates to an improved spirit level and seeks among other objects, to provide a device of this character embodying a novel bubble-glass mounting.

5 The invention seeks, as a further object, to provide a device wherein the bubble-glass may be adjustably rocked by the adjusting screws provided and held in adjusted position without appreciable pressure on said 10 screws to work them loose.

A further object of the invention is to provide a novel clip for holding the bubble-glass and wherein the stock of the level will be formed in an improved manner to accommodate the clip.

15 And the invention seeks, as a still further object, to provide a device wherein the bubble-glass will be so mounted that expansion or contraction of the glass cannot result in fracture of the glass while, at the 20 same time, the glass will be firmly held upon the clip therefor.

Other objects of the invention not specifically mentioned in the foregoing will 25 appear during the course of the following description.

In the accompanying drawings:

Figure 1 is a side elevation of my improved level, parts being broken away and 30 shown in section.

Figure 2 is an edge elevation of the level looking at the bottom edge thereof.

Figure 3 is an enlarged sectional view on the line 3—3 of Figure 1, looking in the 35 direction indicated by the arrows.

Figure 4 is a perspective view particularly showing one of the bubble-glass clips as employed near the ends of the level stock.

Figure 5 is a perspective view showing 40 the bubble-glass clip employed at the middle of the stock.

In carrying the invention into effect, I employ a stock 10 which is preferably of wood, and formed in the stock near each 45 end thereof is a transverse sight opening 11, at opposite sides of which are smaller openings 12 and 13, the latter opening being connected with the sight opening 11 by an intervening slot. Intersecting each of the 50 openings 11 is a pair of alined flat openings 14 and 15, and lying in a plane with each pair of openings 14 and 15 is a slot 16 opening through the top and bottom edges of the stock.

55 Mounted in each of the slots 16 is a clip 17, one of which is shown in Figure 4 of

the drawings. Each of these clips is preferably formed from a piece of suitable resilient sheet metal bent medially to define overlapping wings 18 which are provided with 60 registering sight openings 19, and projecting from the lower edges of said wings are like lugs 20. Above the openings 19, the wings are bowed to define mating semi-cylindrical portions of a sleeve 21 while below said openings the lugs 20 are similarly bowed to define the mating semi-cylindrical portions of a somewhat longer alined sleeve 22. As shown in Figure 1, the sleeves 21 and 22 of the clips are accommodated in the 70 openings 14 and 15 of the stock, and extending transversely through the lugs 20 of said clips at the sleeves 22, are pivot screws 23 supporting the clips for rocking movement within the slots 16. As will be observed, 75 the wings of the clips project into the openings 12 and 13, and screwed through the stock from the bottom edge thereof to contact with the lower edges of the clips near the ends thereof, are adjusting screws 24, 80 countersunk in the stock.

Clamped at their ends in the sleeves 21 and 22 of the clips 17 are bubble-glasses 25, and wrapped about the ends of the glasses are yieldable gaskets 26. These gaskets may be 85 formed of rubber filled fabric tape, ordinary electrician's tape, or other suitable material, and, as shown in Figure 3, completely surround the ends of the bubble-glasses to provide cushioning elements lying between 90 the ends of the bubble-glasses and the sleeves of the clips. As shown in Figure 2, the slots 16 are of a width to snugly receive the clips so that the wings 18 of the clips will be more or less tightly held together 95 for clamping the sleeves about the gaskets 26 so that the bubble-glasses will thus be firmly held upon the clips. At the same time, the gaskets will serve to cushion the bubble-glasses against shock and will accommodate any expansion or contraction of the 100 glasses to prevent fracture thereof.

As will now be seen in view of the foregoing, by adjusting the screws 24, the clips 17 may be rocked in the slots 16 of the stock 105 10 for accurately adjusting the position of the bubble-glasses 25 with respect to the ends of the stock 10 and by advancing the pair of screws associated with each clip until the inner ends of the screws abut the clip, 110 the clip will be firmly held in adjusted position. However, in order to thus hold the

clips in adjusted position, the screws need not be advanced to unduly bind against the clips so that the screws will not be subjected to any pressure such as would result in 5 loosening of the screws. Should one of the bubble-glasses become broken, the clip of said glass may, by removing the pivot screw 23 of the clip, be readily pushed from its slot 16 of the stock, when the wings of the 10 clip may, as suggested in Figure 4, be swung apart to free the broken bubble-glass and permit the ready insertion of a new glass. The clip may then, of course, be readily replaced, as will be at once understood in view 15 of the foregoing description, when the adjusting screws of the clip may be reset for adjusting the position of the bubble-glass.

In conjunction with the bubble-glasses near the ends of the stock, I also provide a 20 bubble-glass at the middle of the stock. Formed in the stock at a point substantially mid-way between the ends thereof is an elongated sight opening 27, and intersecting said opening is a pair of aligned flat openings 25 28 and 29 similar to the openings 14 and 15. Lying in a plane with the openings 28 and 29 is a slot 30 like the slot 16, and snugly accommodated in the slot 30 is a clip 31, shown in detail in Figure 5 of the drawings. 30 This clip is preferably formed from a piece of suitable resilient sheet metal bent upon itself to provide overlapping wings 32, and formed in said wings are registering sight openings 33, at the ends of which are sleeves 34. Formed on the wings, at their lower 35 edges, are mating lugs 35, and extending through said lugs across the opening 29 of the stock is a pivot screw 36 mounting the clip for rocking movement. Clamped at its 40 ends in the sleeves 34 is a bubble-glass 37 like the bubble-glasses 25, and surrounding the ends of the glass 37 are gaskets 38 like the gaskets 26. Extending through the stock from the bottom edge thereof are 45 countersunk adjusting screws 39 which are like the screws 24 and are disposed to coat with the ends of the clip, the screws being adjustable, as will be understood in view of the foregoing description, for rocking the 50 clip and adjusting the position of the bubble-glass 37. The slot 30 is, of course, of a width to snugly receive the clip 31 so that the sleeves 34 will be firmly held about the 55 ends of the bubble-glass while, however, the gaskets 38 will accommodate expansion or contraction of the glass and, as will be seen, the bubble-glass may be viewed from the upper edge of the stock through the opening 28. As will be observed, the lower edges 60 of the wings of the clip 31 are visible at the

bottom of the opening 27 of the stock and, likewise, the lower edges of the wings of the clips 17 are visible at the openings 12 and 13 of the stock. Accordingly, in adjusting the pairs of screws 24 and 39, the operator 65 may see that both screws of each pair abut the lower edges of the clips respectively, while also, mutilation of the clips by the improper adjustment of the screws may be avoided. 70

Having thus described the invention, what I claim is:

1. A level including a stock having a slot therein and provided with a sight opening extending transversely of the slot and intersecting the same, a clip formed from a strip of material folded to provide coating wings, the clip being snugly accommodated in said slot whereby the wings thereof are held in abutting relation, said wings being 80 formed with registering openings alined with the sight opening of the stock and being crimped to form a sleeve intersected by the registering openings, a bubble glass clamped between the sleeve forming portions of said wings and extending across the sight openings of the clip and stock, means pivotally mounting the clip upon the stock, and means adjustable upon the stock for engaging the clip at opposite sides of the pivot means 90 and rocking the clip to adjust the position of the bubble glass relative to the stock. 95

2. A level including a stock formed with a slot, the stock being also formed with a sight opening intersecting the intermediate portion of said slot and with other sight openings intersecting the end portions of the slot, a clip consisting of a strip of resilient material folded to provide companion wings, said wings having registering sight openings therein and at opposite sides of their sight openings crimped to provide sleeve portions, a bubble glass extending across the sight openings of the wings and having its end portions seated in the sleeve portions of the wings, said clip being fitted into the slot of said stock with the bubble glass in operative relation to the first sight opening of the stock and the end portions of the clip viewed through the other sight openings of the stock, adjusting screws threaded into the stock and having end portions visible through the last-mentioned sight openings thereof and engaging the end portions of said clip, and a pivot carried by said stock and engaging said clip intermediate its ends. 105 110 115

In testimony whereof I affix my signature.

JACOB DAY. [L. s.].
